UNITED STATES PATENT OFFICE.

A. INGRAM PARSONS, OF NEW YORK, N. Y.

ROCK-DRILL.

SPECIFICATION forming part of Letters Patent No. 319,308, dated June 2, 1883.

Application filed December 26, 1883. (No model.)

To all whom it may concern:

Be it known that I, A. INGRAM PARSONS, a citizen of the United States, residing at New York, in the county of New York and State 5 of New York, have invented certain new and useful Improvements in Rock-Drills, of which the following is a full, clear, and exact description.

This invention is in the nature of improvements in hand-power rock-drills; and the improvements relate to the means for imparting the compound reciprocating and rotary motion to the drill-spindle necessary to give the tool the proper entrance and clearance of the 15 hole; also, to the operating mechanism, and also to the means for feeding the drilling mechanism as the work progresses.

The invention consists in the mechanisms and combinations of mechanisms, as herein- 20 after particularly set forth and claimed.

In the accompanying drawings, illustrating my invention, in the several figures of which like parts are similarly designated, Figure 1 is a top plan view of my rock-drill, one of the 25 handle-sockets being in section to show its spring. Fig. 2 is an elevation of the near or lower side of Fig. 1, some parts being broken away to show others, the parts being in position just after the delivery of the blow by the hammer. Fig. 3 is an elevation of the far or 30 upper side of Fig. 1, some parts also being broken away to expose others, the parts being in the position assumed immediately preceding the delivery of the blow. Fig. 4 is a 35 plan view of the cam and its shaft, showing in horizontal section the mechanical movement employed in converting the reciprocating motion of the operating-handles into rotary motion of the cam-shaft and its connected parts. Fig. 5 is a vertical section on the plane of the 40 line x x of Fig. 2, looking in the direction of the arrow in said figure. Fig. 6 is a horizontal section on the plane of the line y y , Fig. 5, looking in the direction of the arrow in said 45 figure. Fig. 7 is a perspective view on a larger scale of the worm, pawl, and ratchet, and connection with the spindle for use in connection with the mechanism for automatically feeding the drill. Fig. 8 is a partly sectional elevation on the same scale of the clutch and worm 50 for use in rotating the spindle and manually

feeding the drill. Fig. 9 shows face views of the clutch, and Fig. 10 is a cross-section of part of the mechanism for converting the reciprocating motion of the handles into rotary motion. 55

The drill-frame consists of parallel bars, preferably tubes a a , connected at their ends by yokes a' a' , the yoke a' , at the front of the machine, extending below the plane of the 60 drill-tool, and having the supporting screw-spur a^3 , and the yoke a^2 arching above the bars to provide for the arc of travel of the hammer. These yokes, furthermore, sustain bars b b' , preferably rectangular in cross-section, 65 the bar b having its under surface toothed, and, in consequence, hereinafter designated the rack-bar.

The carriage A, carrying the spindle and hammer and their operating mechanism and 70 the mechanism for operating in connection with the rack-bar for feeding the drill, and which several parts constitute the drill proper, is composed of two side pieces, c c , and a transverse connecting spindle-socket, c' , and 75 said carriage is supported on the drill-frame by the bars b b' , engaging sideways c^2 c^3 on said carriage. By this construction of the frame and the connection therewith of the carriage or drill proper the latter may be 80 freely placed upon and removed from the former, thus largely simplifying the putting together of the parts and the operation of the drill. The drill is supported in working position by the usual struts, d d , and couplings 85 d' , substantially as in the invention set forth in my Letters Patent for the same, numbered 302,424, dated July 22, 1884, or in other approved manner admitting of the setting or adjusting of the drill to the work to be done. 90 The hammer e has its helve e' set in a stock, e^2 , which is supported on a shaft, e^3 , borne between and in the lower ends of the carriage A, and said stock has a friction-roller, e^4 , supported between arms e^5 of this stock, and said 95 stock also has arms e^6 , combined with springs e^7 , acting against abutments e^8 of the carriage, all substantially as in my said invention. The hammer is oscillated by the engagement of the wipers or toes of the double cam f , mounted on the shaft f' , borne by the carriage A, 100 and the force of the blow may be varied by

increasing or diminishing the leverage of the arms e^6 with respect to the springs, a plurality of holes for the attachment of such springs being provided in said arms for this purpose, 5 as shown. The cam f also operates the spindle-retracting lever g , which is fulcrumed on a pin, g' , in the carriage A , said lever being forked at its upper end to engage the spindle.

The cam is rotated continuously in one direction by means substantially as follows: h is a shaft borne by the carriage A , and having fast to it at each end outside the carriage one half, h^1 , of a clutch-box, from which depends the arm h^2 . The other half, h^3 , of the clutch-box has a socket, h^4 , to receive the handle, and this half is held normally in engagement with the other by a spring, h^5 , Fig. 1, the halves of each clutch-box being connected by teeth projecting from their meeting faces in planes radial to the shaft h . The sockets for the handles are made as clutches, to permit the placing of the handles at the most convenient angle for operating the machine under its location and conditions of use, and 25 the socket parts h^4 form convenient grips or hand-pieces for adjusting the angles the parts h^3 shall have with respect to the parts h^1 . At opposite ends of the shaft f' are arranged boxes i , the outer half of each being broken 30 away in Figs. 2 and 3 to expose the interiors, and these boxes are duplicates, except to the extent of being rights and lefts. The top of the inner half of one box and the outer half of the other box have a toothed portion, i' , 35 with which engage pinions j on opposite ends of the shaft f' , and the bottom of the outer half of one box and the inner half of the other are likewise toothed, as at i' , Figs. 4 and 10, and with this toothed portion of each box engage other similar pinions, j' , also on opposite ends of said shaft f' . These boxes i are connected by arms i^3 with the arms h^2 of the handle-socket clutch-boxes, and such connection may be variable, as by a plurality of 45 holes in the arms h^2 , to adjust the length of throw of the boxes, if need be. The pinions j, j' are connected to the shaft f' by spring-dogs j^2, j^3 , respectively, (see Fig. 4,) having reverse engaging-points with their respective pinions, 50 so that as the boxes are moved backward one pair of the pairs of pinions will be fast on the shaft f' and cause its rotation, while the other pair will be loose and slip on said shaft, and on the reverse or forward motion the other and 55 formerly loose pair of pinions will be fast on said shaft and rotate it in the same direction as the first pair, while said first pair will be inoperative or idle with respect to the shaft. The rotation of the pair of pinions fast on the shaft is effected in each instance by the toothed portions of the boxes i engaging said pinions. The rectilinear reciprocations of the boxes or the oscillations or rocking of the operating-handles are thus converted into a continuous rotary motion of the cam-shaft in one direction. The 60 rotary motion of the cam-shaft f' is transmit- 65

ted by a sprocket-wheel, k , and a chain, k' , to a sprocket-wheel, k^2 , on a shaft, l . This shaft l is arranged transversely of and in the carriage A , beneath the spindle-socket, and has (see 70 Figs. 5 and 6) a worm, l' , which meshes with a worm-wheel, l^2 , on the drill-spindle m . This worm-wheel is secured to the spindle loosely and yet to turn it by a spline, l^3 , engaging a longitudinal groove, m' , in the spindle, said groove extending from near the head of the spindle to its rear end, and permitting the spindle to slide through the worm-gear in its longitudinal reciprocation. The wheel is arranged in a boxing, c^3 , of the spindle-socket, 75 turns in it with the spindle, and is held by it as the spindle slides back and forth through it. This worm and worm-wheel give to the spindle the rotation necessary to present different points of the tool in the hole being 80 drilled at different places in such hole, and to effect its ready entrance and clearance of said hole. The drill-spindle is retracted by the lever g engaging a shouldered nut, n , at its rear end, which nut confines a removable striking-pin, and the spindle is projected by a spring, o , coiled around it, all substantially as in the 85 invention before referred to.

Instead of feeding the drill on its supports, as in said invention, I herein employ a worm, 90 p , Figs. 5, 6, and 7, suitably supported, as upon brackets, within the carriage A , which worm has a ratchet, p^1 , and a pawl, p^2 , to engage it. This pawl engages the ratchet to give the worm a tooth-by-tooth rotation, and it is 95 operated by a lever, q , on which it is mounted, and which lever is fulcrumed, say, on the worm-shaft. This lever is jointed to a rod or bar, q' , which in turn is swiveled to a ring, q^2 , secured on the spindle m , so as to reciprocate 100 but not rotate with said spindle. This worm engages a worm-wheel, r , on a shaft, r' , at right angles thereto, said shaft being supported in and transversely of the carriage A . This shaft r' is shown provided with a detachable 105 collar, r^2 ; but the same may be made solid thereon, and the outer end thereof is adapted to be engaged by a sliding pinion, s , receiving within it the inner end of the shaft r' , and having a gudgeon or journal, s' , which has a 110 bearing on the carriage A . This journal s' has two annular grooves, s^2, s^3 , to be engaged by a latch, t , to hold it in and out of engagement with the collar r^2 .

A simple mode for providing for the engagement of the collar r^2 and pinion s is to make a squared or angular socket, r^3 , in the face of the said collar and an aligned projection, s^4 , on the pinion s . The pinion is engaged with or disengaged from the said collar 115 by movement in a longitudinal direction on the shaft r' . This pinion meshes with the rack-bar b , and when rotated moves the drill progressively along the supporting frame. This movement of the drill may be accomplished positively by disengaging the pinion s from the collar r^2 or its worm-wheel. 120 125 130

r, and rotating said pinion by a crank-handle applied to its journal *s*, and it may be had automatically by throwing the pinion into engagement with the collar *r*² or its worm-wheel *r*, in which latter case the pinion will rotate with the said worm-wheel and so feed the drill commensurately with the progress of the boring. The provision of manual positive movement of the drill on its frame is useful in setting or adjusting the drill initially, and for running it back to the rear end of the frame when it has reached the fore end of such frame, and for running the carriage on and off the frame. The several worms and worm-wheels and the spring and that end of the spindle are protected from dust and grit by a cap or shield, *u*, fast to the frame, and the boxes *i* subserve a like purpose for the gearing therein. The handles may be independently adjusted, but their clutch members *h* being fast on the shaft *h*, said handles must be moved in unison to drive the machine.

The collar or swivel *q*² is connected to move with the spindle in any suitable manner, as by collars.

I am aware that it is old to drive a drill by a spring-hammer and retract and partially revolve the same by bell-crank levers and suitable connections, the hammer and levers being operated by wiper-cams. In such a drill before the blow of the hammer and after the partial rotation the drill is borne by a spring against the rock, and the rotating lever is connected to a swinging pawl-plate, the pawl of which engages with a ratchet-wheel concentric with the plate and feathered to the drill-stock.

I am also aware that the motion-converting mechanism which I have interposed between the handles and cam-shaft is of itself older than my invention; hence I claim it only as an element in my combination.

I do not broadly claim the combination, with an advancing carriage carrying a drill-spindle and drill, a vibrating hammer and operating mechanism therefor, of gearing connecting the hammer-operating shaft with the drill-spindle, consisting of a worm and worm-wheel, a gear-wheel, and connecting-gearing.

I disclaim the combination, in a rock-drilling machine, with a cam-shaft, of clutches thereon composed of toothed members fixed to the shaft, and spring-pressed toothed members to which the operating-handles are secured, which spring-pressed members may engage the fixed members so as to bring the handles to any desired angle to the perpendicular, and also a rock-drill frame composed of parallel guide-bars, upon which the drill-carriage moves, and which are connected by yokes that are curved or bent so as not to interfere with the removal of the carriage.

What I claim is—

1. A rock-drill having a cam and shaft therefor, a hammer operated by said cam, a spindle projected into operative position by a

spring and retracted by a lever operated by the said cam, oscillating handles, and reciprocating gearing interposed between said handles and the cam-shaft to convert the oscillating or reciprocating motion of the handles into rotary motion of the cam-shaft, substantially as described.

2. The combination, in a rock-drill, of a spindle and an encircling-spring, a cam and shaft therefor, and connections for operating the hammer and spindle from said cam, with handles to which a back-and-forth movement is given, and converting-gearing interposed between the handles and cam-shaft, and reciprocating with the handles to convert their reciprocating motion into a rotary motion of the cam-shaft, substantially as described.

3. The combination, in a rock-drill, of a spring-spindle, hammer, spindle-retracting lever, a cam, and a cam-shaft, with pinions on said shaft alternately fast and loose thereon, toothed racks engaging such pinions, and oscillating handles connected with such racks to reciprocate them to cause a continuous one-way rotary motion of the cam-shaft by means of the pinion then fast on it, substantially as described.

4. In a rock-drill, the drill-frame consisting of parallel bars *a a'* and rack-bar *b*, connected at their ends by a lower yoke, *a*, and an upper yoke, *a'*, and the struts *d d* and couplings *d'*, swiveled to bars *a a'*, combined with the drill-carriage containing the drill-tool, hammer for driving it, and means to rotate and reciprocate said drill-tool, and to automatically feed the carriage forward in the frame, and a shifting-pinion adapted to be manually operated in connection with the rack-bar to run the carriage on and off its frame, substantially as described.

5. The combination, with a drill proper having a reciprocating spindle, and a frame provided with a rack-bar, of a shifting gear-wheel, its shaft having a squared end and a worm-wheel, a pivoted latch engaging one of two grooves in the said shaft to lock it in either of two positions, and a worm engaging said worm-wheel and actuated by the spindle, whereby said gear-wheel may be rotated manually or automatically to feed the drill as required, substantially as described.

6. The combination, with a drill-frame having the rack-bar *b*, of the drill-carriage, the drill-spindle therein, means, substantially as described, to reciprocate it, the shaft *r'*, arranged transversely of the spindle in its carriage, and provided with the pinion *s*, engaging such rack-bar, the worm-wheel *r* on said shaft, the worm *p*, arranged in the carriage, the ratchet on the worm-shaft, the pawl to engage such ratchet, and the lever connected with the spindle and operated by its reciprocations to operate the pawl to turn the ratchet and thus rotate the worm, substantially as and for the purpose described.

7. In a rock-drill, the frame composed of

the bars a a' b' and rack-bar b , and the connecting-yokes a' a'' for said bars, and the drill-carriage having the slideways c' c'' to engage the bars b b' , and containing the drill-tool, hammer, and operating devices, combined with a shifting-pinion to engage said rack-bar free of the drill-advancing mechanism, to permit the ready removal from and insertion of the drill-carriage in its frame, substantially as described.

In testimony whereof I have hereunto set my hand this 24th day of December, A. D. 1883.

A. INGRAM PARSONS.
